Judson et al., Parent U.S. Appl. No. 29/311,161, filed Jan. 6, 2009.

Primary Examiner — Rashida Johnson(74) *Attorney, Agent, or Firm* — Nixon & Vanderhye, PC(57) **CLAIM**

The ornamental design for a respiratory mask, as shown and described.

DESCRIPTION

FIG. 1 is a front perspective view showing a respiratory mask according to our new ornamental design;

FIG. 2 is a reverse perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines, shown throughout the views, represent the portions of the respiratory mask, which form no part of the claimed design.

1 Claim, 8 Drawing Sheets(56)
